UNITED STATES PATENT OFFICE.

FRANK L. BUFF, OF WICHITA, KANSAS, ASSIGNOR TO THE UNIVERSAL FLUID VENDING MACHINE COMPANY, INC., A CORPORATION OF KANSAS.

AUTOMATIC FLUID-VENDING MACHINE.

1,319,691.

Specification of Letters Patent.

Patented Oct. 28, 1919.

Application filed November 13, 1917. Serial No. 201,836.

To all whom it may concern:

Be it known that I, FRANK L. BUFF, a citizen of the United States, residing at Wichita, in the county of Sedgwick and 5 State of Kansas, have invented a new and useful Automatic Fluid-Vending Machine, of which the following is a specification.

The device forming the subject matter of this application is adapted to be used for 10 dispensing gasoline and like liquids in predetermined quantities. The gasoline is under the control of a valve which has two functions, in that it establishes communication between a source of supply and a tank, 15 and establishes, also, communication between the tank and an outlet pipe.

The object of the invention is to improve the dispensing mechanism, including the aforesaid valve.

20 It is within the province of this disclosure to improve generally and to enhance the utility of devices of that type to which the present invention appertains.

With the foregoing and other objects in 25 view, which will appear as the description proceeds, the invention resides in the combination and arrangement of parts and in the details of construction hereinafter described and claimed, it being understood that 30 changes in the precise embodiment of the invention herein disclosed, can be made within the scope of what is claimed, without departing from the spirit of the invention.

35 In the accompanying drawings the preferred form of the invention has been shown.

In said drawings:—

Figure 1 is a longitudinal section showing 40 the upper part of the structure, including the tank and the float;

Fig. 2 is a longitudinal section disclosing the bottom part of the structure, a portion of the tank appearing in the view;

45 Fig. 3 is a side elevation, wherein parts are broken away, the opposite side of the device from that depicted in Fig. 2 being shown;

Fig. 4 is a horizontal section approxi- 50 mately on the line 4—4 of Fig. 2;

Fig. 5 is an elevation looking at the inner side of one of the disks and attending parts, portions being successively broken away, in the distance, to the end that re- 55 mote parts may appear;

Fig. 6 is a vertical section taken approximately on the line 6—6 of Fig. 5, parts appearing in elevation;

Fig. 7 is a sectional detail showing the 60 valve;

Fig. 8 is a sectional detail disclosing one of the latches;

Fig. 9 is a sectional detail disclosing a portion of the float operated mechanism;

Fig. 10 is a cross-section taken on the 65 line 10—10 of Fig. 1;

Fig. 11 is a perspective view showing the connector;

Fig. 12 is a fragmental vertical section showing a portion of the mechanism carried 70 by the float.

The device forming the subject matter of this application includes a supporting structure which may be variously fashioned, the same including, in the present instance, a 75 box-like base 1 embodying a front plate 2, a side plate 3 and an intermediate plate 4. The base 1 supports a tank 5 which may have a removable lid 6, the numeral 7 denoting the bottom of the tank, and the tank 80 having a sight-glass 11.

Journalized for rotation in the intermediate plate 4 is a horizontal shaft 36 carrying, as shown at 37 in Fig. 5, a clutch member which is of quadrant form. An annular 85 rib 25 is attached by securing elements 26 to the intermediate plate 4, and within the contour of the rib, the clutch member 37 on the shaft 36 moves. The numeral 33 denotes a disk-like head having a hub 34 90 which is mounted to rotate on the shaft 36, the hub 34 carrying, as shown in Fig. 5, a semi-circular clutch member 35, the ends of which are adapted to coöperate, one at a time, with the quadrant clutch member 37 95 on the shaft 36. The numeral 31 denotes an inner disk adapted to rotate on the hub 34 of the head 33 and having, as shown in Fig. 5, a semi-circular rib 32, inclosing the clutch member 35 and the hub 34 of the 100 disk 33 and operating within the contour of the rib 25 which is attached to the intermediate plate 4.

The numeral 27 denotes an inner coiled spring disposed between the disk 31 and the 105 intermediate plate 4, one end of the spring 27 being attached at 28 in a manner which will be understood from Fig. 5, to the rib 25, on the fixed plate 4 and the other end of the spring 27 being attached to a cross 110

pin 29 carried by the disk 31, as shown in Fig. 6. The disk 31 is supplied with a side projection or lug 43, seen at the top of Fig. 5.

5 The numeral 17 designates an outer disk having a lug 44 (Figs. 5 and 6) adapted to coöperate with the lug 43 on the disk 31. The disk 17 rotates on a reduced hub 39 constituting a part of the shaft 36, the disk 17 being held on the hub 39, for rotation, by a pin 40, one end of which is threaded into the shaft 36, the pin having a wrench head 41, which, with a washer 42, holds the disk 17 in place for rotation as aforesaid. The numeral 38 designates an outer coil spring, one end of which is attached to the pin 29, the other end of which is attached to the edge of the head 33, in the same manner in which the spring 27 is attached at 28 in Fig. 5 to the rib 25 on the fixed intermediate plate 4. The outer disk 17 is peripherally supplied with a cam 24, (Figs. 2 and 5) the function of which will be made manifest hereinafter. There is a radial slot 18 in the outer disk 17. 10 In the slot 18, a latch 19 operates, the latch being mounted to move in a groove 15 formed in a head 14 secured as shown at 16 (Fig. 2) to the disk 17. The latch 19 is pivotally mounted on the head 14, as indicated 15 at 20 (Figs. 5 and 6). One end of a leaf spring 21 is attached to the head 14 by means of a securing element 22, the spring having an opening 23 through which one end of the pin 40 passes. The spring 21 engages the inner end of the latch 19, and tends 20 to throw the outer end of the latch 19 away from the exposed face of the disk 17. The latch 19 and the spring 21 adapt the structure claimed to a coin-controlled mechanism. 25 The parts 19 and 21 are mentioned merely because they are incorporated, in a mechanical sense, with one member of the liquid-dispensing mechanism, the object in alluding 30 to the parts in question being to avoid the possibility of confusion. By means of a pin 12 the head 14 is attached to a shaft 8 journalized in the side plate 3 of the base 1 and provided, exteriorly of the side plate, with a handle 9 which is normally in engagement with a stop 10 on the side plate 3. 35

An arm 45 is located on the opposite side of the fixed plate 4 from the disks 31 and 17 and is attached by means of a pin 46 to the shaft 36. The arm 45 is provided with a striker 47, adapted to coöperate with a buffer 48 mounted on the intermediate plate 4. The numeral 49 designates a latch having reduced neck 50 adapted to slide in a slot 51 (Figs. 3 and 8) formed in the intermediate plate 4. A cross piece 52 is secured at 53 to the neck 50 of the latch 49 and includes an outstanding foot 54 standing in the path of the cam 24 on the outer disk 17. The disk 31 includes a radial extension 55 60 carrying a striker 56 adapted to cooperate

with a buffer 57 on the fixed plate 4. A shaft 59 is journalized in the extension 55 and carries, at one side of the extension, a grooved wheel 58, having three internal projections, or rollers, 60, mounted on shaft 60^a 70 in the wheel. Disposed on the opposite side of the extension 55 and secured to the shaft 59 is a triangular pawl 66. A spring strip 61 is attached to the edge of the disk 17 and bears on the projections or rollers 60, two at 75 a time, to hold the shaft 59 releasably against rotation, and to enable the pawl 66 to exercise its office.

At 62 there is shown a hooked latch where-with the pawl 66 is adapted to engage, the latch being carried by a shaft 63 journalized in the intermediate plate 4. The latch 62 is disposed on one side of intermediate plate 4, and on the other side of the intermediate plate there is an arm 64 which is attached 80 to the shaft 63. The lower end of a plunger 65 is pivoted as indicated at 65^a in Fig. 3 to the free end of the arm 64, the plunger including a shoulder 67 against which abuts the lower end of a helical-compression spring 90 68 carried by the plunger, the upper end of the spring engaging a washer or rider 69 wherein the plunger 65 reciprocates. The plunger 65 is slidably received in openings 70 formed in a tubular bearing 71 carried 95 by a hanger 72 mounted on the intermediate plate 4. A shaft 73 is mounted to rock in the bearing 71 and extends through the intermediate plate 4, the shaft having, as shown in Fig. 9, a triangular opening 74 100 wherein the upper end of the plunger 65 is received.

Passing to Fig. 2, it will be observed that an arm 75 is attached to the shaft 73, the arm 75 being located on the opposite side of intermediate plate 4 from the plunger 65. The arm 75 is pivoted at 75^a to the lower end of the rod 76 slidable in a guide tube 77 carried by part 7 of the tank 5. The upper end of the rod 76 is secured at 78 110 (Fig. 1) to a tube 79 mounted to slide on the outside of the guide tube 77. The tube 79 has a key 80 engaged in a keyway 80^a formed (Fig. 11) in one of a plurality of yieldable fingers 81 upstanding from a base ring 83 115 shown in Fig. 13. A nut 82 is threaded upon the fingers 81 and compresses the same on tube 79. The base ring 83 is located within an outer ring 85 and is pivoted at 84 thereto, the outer ring 85 being pivoted at 120 86 to a neck 87 upstanding from a float 88 in the tank, the tube 79 passing through the float. The key 80 prevents the float 88 from rotating, and by moving the nut 82, the hold of the fingers 81 upon the tube 79 may be 125 loosened or tightened, thereby permitting the float 88 to be adjusted vertically on the tube 79.

Disposed on the opposite side of the intermediate plate 4 from the disks 17 and 31 130

and secured thereto at 89^a is a bracket 89 carrying a valve casing 90 in which is journaled a valve 91 (Fig. 7) having an L-shaped passage 92. The valve 91 is operatively united with one end of the shaft 36 by means of a connector 93 shown in Fig. 12. The valve casing 90 has side ports 95 and 96 and a top port 94. A pipe 97 forms a communication between the valve casing 90 and the tank 5 and communicates with the port 94. A lateral discharge hose 98 is carried by the casing 90 and communicates with port 95. The numeral 99 marks a depending pipe which is adapted to communicate with a source of liquid supply for the port 96.

When the device is not in use, the angular passage 92 in the valve 91 is so arranged that the passage communicates with the port 94 and with the pipe 97 leading to the tank 5, and with the discharge hose 98.

In order to operate the machine, the handle 9 is swung away from the stop 10, rotation being imparted to the outer disk 17 in the direction of the arrow A of Fig. 5 by way of the shaft 8 and the head 14. The cam 24 on the disk 17 passes from beneath the foot 54 on the cross piece 52, and the latch 49 moves downwardly in the slot 51 of the forked plate 4 until it lies in the path 80 of the arm 45, thereby holding the arm against movement and preventing a rotation of the shaft 36. When the outer disk 17 is further rotated, the lug 44 on the disk 17 engages the lug 43 on the disk 31, and both disks are rotated together. When the disk 31 is rotated, the spring 27 is put under tension, because one end of the spring is attached by means of the pin 29 to the disk 31, and because the other end of the spring is attached at 28 to the rib 25 on the fixed intermediate plate 4. When the disk 31 is rotated, as aforesaid, the spring 38 is put under tension, because one end of the spring is attached to the pin 29 in the disk 31, and because the other end of the spring is attached to the disk or head 33. The head 33 remains fixed, during the operation above described, since, as shown in Fig. 5, the semi-circular clutch member 35 on the hub 34 of the head is engaged with the clutch member 37 of the shaft 36, and the shaft 36 cannot rotate, for the reason that the arm 45 which is attached to the shaft is inter-engaged with the latch 49. When the inner disk 31 is rotated, pawl 66 which is carried by the extension 55 of the disk 31 rotates through a slight arc as it passes the head of the latch 62 and is held engaged with the latch 62 by the action of the spring 61 on two of the projections or rollers 60 on the extension 55 of the disk 31. The latch 62 is pressed toward the right in Fig. 2 by the pawl 66, as the third projection moves into engagement with the latch, the shaft 63 is rotated through a small arc, the free end of the arm 64 being raised,

and the plunger 65 being raised also, the plunger abutting against the bearing 71 at one side of the upper opening 70. The plunger 65 cannot slide upwardly through the upper opening 70 at this time, because the shaft 73 has been rotated by the weight of the float 5, tube 79, the rod 76 and the arm 75 so that the shaft directs the end of the plunger against the inner surface of the bearing 71 at one side of the upper opening 70 in the bearing.

The operator now brings the handle 9 back to its original position against the stop 10. The outer disk 17 is restored to its original position also, the cam 24 lifting the latch 49, through the instrumentality of the cross piece 52 and the foot 54. When the latch 49 is raised, the arm 45 is released. The spring 38 reacts on the disk 31 and the arm 45 swings to the left (Fig. 3) until striker 47 on the arm engages the fixed buffer 48 on the plate 4. The clutch member 35 on the hub 34 of the head 33, coacting with the clutch member 37 on the shaft 36, rotates the shaft, motion being transmitted to the valve 91, and the valve being rotated with a snap until the striker 47 on the arm 45 has engaged the fixed buffer 48 as hereinbefore mentioned. When the valve 91 is rotated, the angular passage 92 in the valve 91 is shifted from communication between the ports 94 and 95, to communication with the ports 94 and 96.

Fluid now traverses the pipe 99 from the source of supply and moves through the ports 96, 92 and 94, into the tank 5, by way of the pipe 97. When a predetermined amount of liquid has accumulated in the tank 5, the float 88 is raised, thereby raising the tube 79 and the rod 76. When the rod 76 is raised (note Fig. 2) the arm 75 is swung upwardly, rotating the shaft 73, and when the shaft 73 is rotated (see Fig. 9) the shaft directs the upper end of the plunger 65 into alignment with the upper opening 70 in the bearing. The plunger 65 now moves upwardly under the thrust of the pawl 66 on the latch 62, and the latch 62 is disengaged from the pawl 66, whereupon the inner disk 31 rotates back to its original position, due to the energy which has been stored in the spring 27. When the inner disk 31 is restored to its original position, the clutch member 32 on the disk 31, coacting with the clutch member 37 on the shaft 36, rotates the shaft and swings the arm 45 over until it passes beneath the latch 49, as shown in Fig. 3. By the operation last above described, the valve 91 is turned back to the position of Fig. 7, so that the angular passage 92 communicates with the ports 94 and 95, a measured quantity of gasoline flowing from the tank 5 through the pipe 97, through the ports 94, 92 and 95, and out of the discharge hose 98.

Having thus described the invention, what is claimed is:—

1. In a device of the class described, first and second rotatable members; means under the control of an operator for rotating the first member forwardly and rearwardly; inter-engaging elements upon the first and second members whereby the first member will impart forward rotation to the second member; first and second springs tensioned when the second member is rotated forwardly; a third rotatable member whereto the first spring is connected; a valve shaft; clutch elements on the third member, on the shaft and on the second member, the clutch elements of the third member and of the shaft co-acting to hold the third member against rotation when the second member is rotated forwardly; means for holding the shaft and for setting it free, comprising a latch responsive to the rearward rotation of the first member for releasing the latch and an element carried by said shaft and coacting with the latch to hold the shaft; mechanism for holding the second member against the tension of the spring which tends to cause backward rotation of the second member; and float controlled means for releasing said mechanism, the clutch elements of the second member and of the shaft backwardly co-operating to rotate the shaft sufficiently to permit the shaft carried element to engage with the latch when said mechanism is released. 80
2. A device constructed in accordance with claim 1, and further characterized by the fact that the latch is activated by a cam on the first member, and that the shaft carried element consists of a radial arm automatically engaging with the latch. 90
3. A device constructed in accordance with claim 1, and further characterized by the fact that the mechanism for holding the second member against backward rotation comprises a pawl on the second member and a shaft mounted to rock, the shaft carrying arms, one of which coacts with the pawl, the other of which is connected with the float controlled means. 100
4. A device constructed in accordance with claim 1 and further characterized by the provision of relatively fixed buffers wherewith the shaft carried element and the second member coact to relieve the shock 110 incident to the action of the springs. 120
5. A device constructed in accordance with claim 1 and further characterized by the provision of a plunger pivoted to a part of the holding mechanism; a second shaft through which the plunger passes; an arm carried by the shaft; the elements above specified constituting the float controlled means; and a float operatively connected with the arm. 130
6. In a device of the class described, a tank; a casing having a port communicating with the tank, an inlet and an outlet; a valve in the casing, the valve in its first position connecting the port with the outlet, the valve in its second position connecting the inlet with the port; spring means for moving the valve from its first position to its second position; reversely rotatable mechanism under the control of an operator for first tensioning the spring means and then releasing the valve to the action of the spring means to move the valve from its first position to its second position; and means for restoring the valve to its first position. 140
7. In a device of the class described, a tank; a casing having a port communicating with the tank, an inlet and an outlet; a valve in the casing, the valve in its first position connecting the port with the outlet, the valve in its second position connecting the inlet with the port; spring means for moving the valve from its first position to its second position; reversely rotatable mechanism under the control of an operator for tensioning the spring means and then releasing the valve to the action of the spring means to move the valve from its first position to its second position a second spring means for moving the valve from its second position back to its first position; and tensioned by said reversely rotatable mechanism; mechanism for holding the second spring means under tension; a float in the tank; and an operative connection between the float and the last specified holding means to release the latter when the float rises. 150

In testimony that I claim the foregoing as my own, I have hereto affixed my signature in the presence of two witnesses.
